The ornamental design for a storage container for magnetic media, as shown and described.

DESCRIPTION

FIG. 1 is a top perspective view of a storage container for magnetic media, showing my new design; FIG. 2 is a bottom perspective view thereof; FIG. 3 is a perspective view thereof, shown open; FIG. 4 is a rear elevational view of FIG. 1; and, FIG. 5 is a top plan view of FIG. 3.

FIG. 1

FIG. 2

FIG. 3

FIG. 4

FIG. 5
